[57] CLAIM

The ornamental design for a rubber gripper holder for a conveyor chain, as shown and described.

DESCRIPTION

FIG. 1 is a top plan view of a rubber gripper holder for a conveyor chain showing my new design;
FIG. 2 is a side elevational view thereof, the opposite side elevational view being a mirror image of that shown;

FIG. 3 is a front elevational view thereof;

FIG. 4 is a rear elevational view thereof;

FIG. 5 is a bottom plan view thereof;

FIG. 6 is a top perspective view thereof; and

FIG. 7 is a bottom perspective view thereof.

FIG. 1

FIG. 2

FIG. 3

FIG. 4

FIG. 5

FIG. 6

FIG. 7
